UNITED STATES PATENT OFFICE.

JAMES H. PORCUPILE, OF PARKERSBURG, IOWA.

REFRIGERATOR.

SPECIFICATION forming part of Letters Patent No. 224,222, dated February 3, 1880.

Application filed July 12, 1879.

To all whom it may concern:

Be it known that I, JAMES H. PORCUPILE, of Parkersburg, in the county of Butler and State of Iowa, have invented a new and valuable Improvement in Refrigerators; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal central vertical section of my refrigerator, and Fig. 2 is a top view thereof with the lid removed.

This invention has relation to improvements in refrigerators; and the nature of the invention consists in combining, with an insulated ice-box or refrigerator, constructed as described, and having a lid, removable or hinged, and likewise insulated, an inclined ice-receptacle having close sides, ends, and bottom, a waste-pipe extending to the outside of the box, and having its higher edge in close contact with the insulated lid, and grooves cut in the under side of the lid, extending beyond the said receptacle, as will be hereinafter more fully described.

In the annexed drawings, the letter A designates a rectangular wooden box, having at its bottom, sides, and ends the double walls *a a'*, forming the air-chambers *b*, and provided with a lid, *c*, also having double walls, *d*, and an air-chamber, *d'*. This lid has extending through it a metallic tube, *e*, the object of which will hereinafter appear, and access is had to the interior of the box through a double walled and chambered door hinged to its sides. In between the double walls, and resting against the inner ones, is a sheet of stout pasteboard, *f*, that effectually prevents the atmosphere of

the interior of the box from being affected by the atmosphere outside, the said board being a very poor conductor of heat. To this result the chambers between the double walls materially assist.

B indicates the ice-receptacle, arranged upon a rack, *g*, at the upper part of the box, in an inclined position, and having a drip-spout, *h*, extending through the side thereof. The upper edge of this receptacle, at one end, fits snugly against the under side of the lid, as shown in Fig. 1. Below rack *g* are other racks, *g'*, to receive fresh meats and other perishable articles. As the atmosphere of the box becomes lowered by the ice the coldest and heaviest currents pass out of the same at its right-hand end, through the grooves *l* in the under side of the lid, and sink down upon the provisions on the racks, where they lose much of their frigidity, become lighter, and rise, passing out of the refrigerator through the tube in its lid.

What I claim as new, and desire to secure by Letters Patent, is—

In a refrigerator, the combination, with the box *A*, having an air-chamber, *b*, and provided with a chambered lid or cover, *c*, of the ice-receptacle *B*, having that edge next to the air-escape tube *e*, provided in the upper part of the box, resting against the under side of the lid *c*, to prevent the immediate escape of the colder currents of air from the receptacle *B*, holding the ice, substantially as and for the purpose set forth.

In testimony that I claim the above I have hereunto subscribed my name in the presence of two witnesses.

JAMES H. PORCUPILE.
